UNITED STATES PATENT OFFICE.

MARY ELEANOR RUDY, OF LOS ANGELES, CALIFORNIA.

COMBINED FOLDING TABLE AND LUNCH-BOX.

1,317,895.

Specification of Letters Patent.

Patented Oct. 7, 1919.

Application filed January 9, 1919. Serial No. 270,342.

To all whom it may concern:

Be it known that I, MARY ELEANOR RUDY, a citizen of the United States, residing at Los Angeles, in the county of Los Angeles 5 and State of California, have invented certain new and useful Improvements in Combined Folding Tables and Lunch-Boxes, of which the following is a specification.

The invention provides a device which 10 may be used as a table and as a box or case accordingly as may be required, the structure being such as to admit of the parts folding into compact form for convenience of storing and handling and which provides ample space for receiving sundry 15 articles.

The invention is designed more particularly to provide an article for the convenience of pleasure seekers wherein a table 20 is at hand for receiving a luncheon, or to be used for games, or for other purposes where it is desirable to have a table for receiving articles to be supported, the device also providing a case or box which may 25 be utilized for receiving and carrying dishes, table ware, food, chairs and sundry articles, the device furthermore when folded occupying a comparatively small space so as to be conveniently carried in a vehicle, or upon a 30 rack, running board or other desired part of the vehicle. When attached to the running board of an automobile or other vehicle, the same is utilized as supporting means for one end of the table when the 35 latter is extended, the opposite end of the table being supported by a folding leg, or legs.

The drawing illustrates a preferred embodiment of the invention, however, it is 40 to be understood that in adapting the same to meet different conditions, various changes in the form, proportion, and minor details of construction may be resorted to without departing from the nature of the invention 45 as claimed hereinafter.

Referring to the drawings herein attached,

Figure 1 is a perspective view of part of an automobile showing a device embodying 50 the invention mounted on the running board thereof, said device being in folded position.

Fig. 2 is a view similar to Fig. 1, the full lines showing the device partly unfolded and the dotted lines showing the parts ex- 55 tended to provide a table.

Fig. 3 is a side view of a table extended,

the casing being in section and the dotted lines indicating the position of the table when in folded position and when partly folded. 60

Fig. 4 is a view of the table as seen from the under side, the supporting legs being folded and the casing being in section.

Corresponding and like parts are referred to in the following description and indicated in the several views of the drawings by like reference characters. 65

The device comprises essentially two parts, a casing 1 and a folding table, the latter closing the front of the casing when folded 70 therein. The casing 1 is closed at the back, top, bottom and sides and is open at its front, as indicated most clearly in Fig. 2 to admit of the table being readily folded into the casing and withdrawn therefrom when 75 required for use. A strip 2 is disposed at the top of the casing and at the front thereof and receives a strap 3. A strip 4 is located at the bottom of the casing and at the front thereof and receives a turn button 5. 80 A compartment 6 is formed in the lower portion of the casing which may be utilized to receive folding chairs, a thermos bottle or other container or articles of any nature. The casing may be constructed of any suitable material so as to insure lightness, durability and a maximum amount of storage space consistent with the external dimensions of the casing. While it is preferred 85 to mount the device upon the running board 90 7 of an automobile or other type of motor vehicle it is to be understood that it may be constructed so as to be conveniently carried within the vehicle or strapped to any convenient part thereof. For convenience ears 95 8 project laterally from the sides of the casing and are pierced to receive suitable fastening means whereby the device is attached to the running board 7.

The folding table comprises sections 9 100 and 10, the section 9 being pivotally connected to the casing and the section 10 in turn pivotally connected to the section 9 by means of a rule joint as indicated at 11 whereby the sections 9 and 10 are supported 105 in horizontal position when the table is extended as shown most clearly in Fig. 3. The sections 9 and 10 are of similar or like construction, each comprising a top and a frame, the latter inclosing a space and having 110 the top secured thereto in any manner. The space inclosed by the frame is utilized

for storage of the dishes, table ware, food and the like to be carried. The section 10 folds against the under side of the section 9, thereby providing a maximum storage space. 5 The inner section 9 is pivoted at the sides of the casing 1 at 12 and when the table is extended the inner portion of the section 9 rests upon the strip 4, as indicated most clearly by the full lines in Fig. 3, thereby 10 relieving the pivot fastening 12 of undue strain. Folding legs 13 are pivotally connected to the outer end of the section 10 and are stayed by means of braces 14 which are pivotally connected to the section 10 and 15 are adapted to make detachable connection with the legs 13 to admit of the legs and braces folding within the section 10, as shown most clearly in Fig. 4. Strips 15 are provided and spaced a short distance from 20 the side members of the frame to inclose spaces for receiving the legs and braces where the latter are in folded position. The strips 15 serve to stiffen and strengthen the table as will be readily understood. A tray 25 16 is adapted to be secured to the under side of the inner section 9 and may be removed or retained in place in any manner. This tray may receive dishes, table ware, food and the like. A compartment 17 is provided at 30 the inner end of the section 9 and may receive a thermos bottle 18 or other container or may be utilized in any manner for storing sundry articles.

When the parts are properly constructed 35 and assembled the outer section 10 will fold against the under side of the inner section 9 and both sections will fold into the casing 1 so as to close the open front thereof as indicated most clearly in Fig. 1. When the 40 table is in folded position it is secured by suitable fastening means applied to the parts 2 and 4 and to opposite ends of the section 10. The part 2 is movable and partakes of the nature of a flap so as to fold over the 45 upper end of the section 10 and thereby shed water and prevent the same entering the casing. When the table is extended into position for service it is supported at its end by the casing 1 and vehicle to which the casing

is attached and at its outer end by the legs 50 13. Fig. 3.

The foregoing description and the drawings have reference to what may be considered the preferred, or approved, form of my invention. It is to be understood that 55 I may make such changes in construction and arrangement and combination of parts, materials, dimensions, et cetera, as may prove expedient and fall within the scope of the appended claims. 60

Having thus fully described my invention, what I claim as new and desire to secure by Letters Patent is:—

1. In a device of the character specified, a casing having an open front and strips at 65 the top and bottom of the open front, the upper strip being movable, a folding table comprising sections connected by means of a rule joint and pivotally connected at its inner end to the casing and adapted to rest 70 upon the lower strip when the table is extended and a folding support at the outer end of the table to come between the two sections, the outer section of the table folding against the under side of the inner section 75 and closing the front of the casing when the table is folded therein.

2. A device of the character specified, comprising a casing having an open front, and strips at the top and bottom of the front, a 80 folding table comprising two sections connected by means of a rule joint and pivotally connected at its inner end to the lower casing to be supported thereby, a tray supported beneath one of the sections and 85 adapted to be inclosed between the two sections and a folding support at the outer end of the table, the outer section of the table folding against the under side of the inner section and closing the front of the casing 90 when the table is folded.

In testimony whereof I affix my signature in presence of two witnesses.

MARY ELEANOR RUDY.
